CLAIM

The ornamental design for a dispensing station, as shown and described above.

DESCRIPTION

FIG. 1 is a front perspective view of a dispensing station; FIG. 2 is a front elevation view of the dispensing station thereof;

FIG. 3 is rear elevation view of the dispensing station thereof;

FIG. 4 is a left-side elevation view of the dispensing station thereof, the right-side elevation view being a mirror image thereof; and,

FIG. 5 is a top plan view of the dispensing station thereof. The broken lines depict portions of the dispensing station that form no part of the claimed design.
